UNITED STATES PATENT OFFICE.

FORD R. WILBER AND HORACE E. BALL, OF PAW PAW, MICHIGAN, ASSIGNEES TO THE
MOONLIGHT BAIT COMPANY, OF PAW PAW, MICHIGAN.

FOLDING CHAIR.

1,293,592.

Specification of Letters Patent. Patented Feb. 4, 1919.

Application filed June 13, 1917. Serial No. 174,523.

To all whom it may concern:

Be it known that we, FORD R. WILBER and HORACE E. BALL, citizens of the United States, residing at Paw Paw, county of Van Buren, State of Michigan, have invented certain new and useful Improvements in Folding Chairs, of which the following is a specification.

This invention relates to improvements in folding chairs.

Our improved folding chair or seat is especially designed by us as a supplemental seat for boats, circus seats, grand stands, and the like, where a board is commonly provided for a seat.

It is the main object of this invention to provide a collapsible or folding seat adapted for use in the relations indicated, which is very satisfactory for the purpose and at the same time one which is simple and economical to produce and easily applied to or removed from the seat or other support.

Further objects and objects relating to structural details, will definitely appear from the detailed description to follow.

We accomplish the objects of our invention by the devices and means described in the following specification. The invention is clearly defined and pointed out in the claims.

A structure which is a preferred embodiment of our invention is clearly illustrated in the accompanying drawing, forming a part of this specification, in which:

Figure I is a front perspective view of our improved chair applied to a support, such as a boat seat.

Fig. II is a perspective view of our improved chair collapsed.

Fig. III is an enlarged detail side elevation, the seat support being shown in section.

Fig. IV is an inverted detail with the back erected.

In the drawing similar reference characters refer to similar parts throughout the several views.

Referring to the drawing, 1 represents a board-like seat or support, such as the seat of a boat. Our improved seat or chair comprises a seat frame 2 formed of a rod or bar bent into a U-shape. The bight end of this frame is bent downwardly at 3 and rearwardly at 4 to provide a clamping hook adapted to be engaged over the edge of the support 1.

The ends of the arms of the seat frame

2 are turned laterally to provide pintles 5. The back frame 6 is also formed of a piece of rod bent into a U-shape and has coils 7 formed adjacent the ends of its arms providing eyes for the pintles 5. The ends of 60 the arms of the back frame are extended forwardly beyond the coils at 8 and turned laterally at 9 providing stops coacting with the arms of the seat frame for supporting the back in its erected position. 65

The bight of the back frame is preferably offset rearwardly at 10 to bring it out of the plane of the arms. The flexible seat strip 11 is secured to the seat frame by folding its edges over the arms of the seat frame 70 and securing thereto, as by the rivets 12. The flexible back strip 13 is similarly secured to the arms of the back frame.

With the parts thus formed and arranged the chair is economical to produce, may be 75 formed of comparatively light material, and is very easily applied to and removed from the support on which it is desired to use the chair. The structure is easily assembled and disassembled both in manufacturing and as 80 other occasions may require. The spring tension of the arms is sufficient to hold the pintles and eyes in engagement.

Having thus described our invention, what we claim as new and desire to secure by Letters Patent, is:

1. In a chair, the combination of a U-shaped seat frame having its bight end bent downwardly and rearwardly providing a support engaging hook and the ends of its 90 arms bent outwardly providing back pintles, a U-shaped back frame having coils in its arms adjacent the ends thereof providing eyes engaged with said pintles, the ends of the arms beyond said eyes being extended 95 forwardly and turned laterally providing stops coacting with the sides of the seat frame for supporting the back in its erected position, and a back strip secured to the arms of said back frame and constituting 100 means for preventing the spread of the arms and disengagement of the eyes from the pintles.

2. In a chair, the combination of a U-shaped seat frame having its bight end offset 105 downwardly and rearwardly providing a support engaging hook, a U-shaped back frame, the arms of said seat and back frames having coacting eyes and pintles formed therein, one member having the ends of its 110

arms turned laterally providing stops coacting with the arms of the other member, the bight of said back frame being offset rearwardly out of the plane of its arms, and seat 5 and back strips secured at their edges to the arms of said seat and back frames and constituting means for preventing the disengagement of the said pintles and eyes.

In witness whereof we have hereunto set our hands and seals in the presence of two 10 witnesses.

FORD R. WILBER. [L. S.]
HORACE E. BALL. [L. S.]
